ELECTRICAL SWITCH

Michael A. Pastrick, Perth Amboy, N. J.

Application July 31, 1947, Serial No. 765,220

12 Claims. (Cl. 200—167)

(Granted under the act of March 3, 1883, as
amended April 30, 1928; 370 O. G. 757)

1

This invention pertains to the art of electrical switches, and it comprises a novel switch, the disclosed embodiment thereof comprising a throw switch.

This application is a continuation of my co-pending application, Ser. No. 644,984, filed February 1, 1946, for a Switch, now abandoned.

The switch of my co-pending application referred to, and of the present application, comprises companion members that are relatively rotatable in registration on a cylinder of registry between members. The respective companion members accordingly comprise a rotor and a stator, the rotor being rotatable companion to the stator to operate the switch to open or close one or more electrical circuits selectively.

One of the members comprises a surface of cylindrical contour coincident with the cylinder of registry between the members. The other member comprises a notch that projects into the body of the member in a direction away from the cylinder of registry, the notch extending lengthwise of the cylinder of registry. The cylindrical surface is of dielectric material, the preferred practice being to make the member embodying the cylindrical surface of dielectric material. The dielectric cylindrical surface contains inserts of conductor material disposed at intervals lengthwise of the cylinder of registry. The inserts constitute electrical contacts, and each contact is extended through the member for the several contacts to provide terminals for one or more electrical circuits.

The notch of the companion member contains and confines a contactor in the form of a roller that extends far enough lengthwise of the cylinder of registry to reach the several inserts disposed at intervals lengthwise of the cylinder of registry. The roller surface may be cylindrical and of uniform diameter throughout its length. It provides contact cylinders disposed at intervals along its length that correspond with the intervals between inserts disposed lengthwise of the cylinder of registry, the contact cylinders of the contactor being disposed to engage the contacts formed by the inserts.

The internal surface of the notch that engages the contactor is of dielectric material to avoid short circuiting between contact cylinders of the contactor, the preferred practice being to make the member embodying the notch of dielectric material. Resilient means in the notch is disposed in backing relationship with the contactor contained in the notch, the resilient means operating to press the contact cylinders of the roller radially towards the cylinder of registry, and into

2

frictional engagement with the cylindrical surface of the member containing the contacts. Rotation of the rotor relative to the stator causes the roller of one member to roll smoothly on the cylindrical surface of the other member, and causes the contact-cylinders of the roller to roll smoothly into or out of contacting engagement with their respective contacts. In this manner the contact-cylinders operate to close a circuit through the contacts.

A number of different-type contactors can be used, depending upon the characteristics of the circuit or circuits that are desired to be controlled by the switch.

15 One construction of roller comprises a continuous-conductor contactor operable to close a circuit between different spaced apart contacts. It consists of a piece of conductor material that is long enough to bridge the distance between contacts. Those portions at least of its surface that are located to register with and engage the contacts are cylindrical, enabling them to roll smoothly on the cylindrical surface of the companion member into or out of engagement with the contacts.

20 A multiple-contact contactor of different construction comprises spaced apart contact cylinders of conductor material separated and held in spaced relationship by a dielectric piece. The contact cylinders are positioned in the contactor for registration and engagement with respective contacts of the companion member, and the contact cylinders of this type contactor are available as terminals of a circuit which is desired to be connected with the circuit of the terminals of the contacts of the other member.

25 The switch of the disclosure embodies both types of contactors hereinbefore remarked, and these are contained in respective notches spaced apart circumferentially of the cylinder of registry between the rotor and the stator. The different contactors are positioned for alternative engagement with contacts in the companion member by rotation of the rotor relative to the stator. The switch of the disclosure is adapted to be used as an "on-off" switch for an electrical circuit comprising a line and an electrical load in the line.

30 The switch is usable as a light switch in a room, and the circuit controlled by the switch includes a glow-tube disposed in the handle of the switch, the glow-tube being operated to glow when the switch is thrown to "off" position. The present invention includes a switch handle with novel characteristics.

35 The principles of the invention, and the struc-

ture and operation of the embodiment of the disclosure, will be more fully understood from the accompanying drawings, to which attention is now directed. In the drawings—

Fig. 1 is a side elevation of a switch embodying the invention, the switch being in "off" position, and the near side plate being removed to expose the operating parts to view.

Fig. 2 is a cross-section taken on line 2—2 of Fig. 1.

Fig. 3 is a view similar to Fig. 1, showing the switch in "on" position.

Fig. 4 is a cross-section taken on line 4—4 of Fig. 3.

Fig. 5 is a face view of the switch in position for use attached to a wall or the like surface, parts being shown broken away for clearness of illustration.

Fig. 6 is a cross-section taken on line 6—6 of Fig. 5, and

Fig. 7 is a wiring diagram, partly schematic, of an electrical circuit embodying the disclosed switch.

The switch illustrated in the drawings, which constitutes one practical application of the principles of the invention, comprises the companion members 11 and 12 constituting a rotor and a stator, respectively. The rotor 11 is rotatable in the stator 12 in registration therewith on a cylinder of registry.

In the construction shown, the rotor 11 is cylindrical and is preferably constructed of any suitable dielectric material. For example, the rotor 11 can be manufactured as a molded plastic piece. The stator comprises the cylindrical surface 15 that coincides with the cylinder of registry between the members 11 and 12, the diameter of the rotor 11 being slightly smaller for it to rotate freely in the cylindrical surface 15.

In the disclosed embodiment, the periphery of the rotor 11 is provided with the notches 17 and 18 projecting into the body of the rotor in a direction away from the cylinder of registry, the notches 17 and 18 extending lengthwise of the cylinder of registry. The notches 17 and 18 are spaced apart circumferentially by an amount determined by the throw of the switch.

The notch 17 contains and confines the contactor 20, and the notch 18 contains and confines the contactor 21 in a like manner. The contactors 20 and 21 are rollers of different types, being a continuous-conductor type 20 and a multiple-contactor type 21.

Each of the notches 17 and 18 contains resilient means disposed in backing relationship with its roller 20 or 21, the resilient means operating to press the contactors 20 and 21 radially outwardly of their notches towards the cylinder of registry and against the cylindrical surface 15 of the stator 12 in rolling engagement therewith. In the notch 17, the springs 22 comprise the resilient means backing the roller 20, and in the notch 18 the springs 23 and 24 comprise the resilient means backing the roller 21.

The cylindrical surface 15 of the stator 12 is of dielectric material, and pursuant to this purpose the stator 12 is preferably constructed of dielectric material. The stator 12 can be manufactured conveniently as a molded plastic piece. Inserts 26 of a conductor material are disposed in the surface 15, to constitute contactors spaced apart lengthwise of the cylinder of registry as illustrated in Figs. 2 and 4. The conductor material of the inserts 26 preferably extends through

the body of the stator 12 as shown, to provide binding posts 27 or other suitable means to serve as terminals for attaching electrical wiring to the switch.

5 The continuous conductor contactor 20, Fig. 4, of the disclosed embodiment, comprises an elongated piece of conductor material. At least portions spaced apart lengthwise of the contactor 20 are cylindrical for rolling engagement with the cylindrical surface 15 of the stator 12, the contactor 20 of the disclosure being continuously of uniform diameter, and unmarked portions thereof constituting the contact cylinders that are companion to the respective contacts 26 of the stator 12.

10 The contactor 20 being confined in the notch 17 and backed by the springs 22, it is caused to roll on the surface 15 by frictional engagement therewith when the rotor 11 is rotated relative to the stator 12, and by this means the contactor comprising the roller 20 rolls smoothly into and out of contacting engagement with their respective companion inserts 26. The inserts 26 lie substantially flush with the cylindrical surface 15, being preferably raised therefrom a slight amount for good electrical contact, the amount being attained for example by the cord of the arc that the flat faces of the inserts 26 describe. See Figs. 1 and 3. When the contactor 20 rolls 15 into contacting engagement with the contacts comprising the inserts 26, it closes electrical circuit across the terminals 27.

20 The contactor 21 provides contacts respectively companion to the terminals 21, and these are in an auxiliary circuit in series with the line that is connected to the terminals 27. Pursuant to this purpose the multiple-contact type contactor 21, Fig. 2, is an elongated member comprising contact cylinders 29 spaced apart lengthwise of itself, and held in spaced relationship by the dielectric piece 30. The contact cylinders 29 are held with reference to the cylinder of registry located to register respectively with the contacts 26 and to roll into and out of contacting engagement therewith when the rotor 11 is rotated relative to the stator 12.

25 In the case of the continuous-conductor contactor 20, the springs 22 are seated in the dielectric material of the rotor 11, as illustrated in Fig. 4. In the embodiment of the disclosure, the contact-cylinders 29 of the multiple-contact contactor 21 serve as a switch for an auxiliary light circuit through the glow tube 32 in the handle 33 of the rotor 11. Contacts 28 are provided, seated in suitable pockets 31 which are formed in the rotor 11, for example, in the molding operation during their manufacture. The contacts 28 comprise short lengths of tubing, made of any suitable conductor material with resilient properties, and are flattened to fit in the pockets 31, into which they are inserted endwise of the rotor, and in which they are held resiliently.

30 The springs 23 and 24, Fig. 2, are compressed between their respective contact cylinders 29 and the contacts 28 respectively companion thereto, the springs 23 and 24 thus serving as electrical conductors. Resistor 36, which is of predetermined fixed resistance, is inserted in the rotor 11 between companion contacts 28 and 29 together with the spring 24, to be in electrical series therewith and with the auxiliary circuit.

35 The rotor 11 is provided with a handle comprising a body member 33 of translucent material, having a cavity of a size and shape to receive and hold the glow-tube 32. The dielectric plate

34 encloses the tube 32 in the handle body 33, and provides a convenient terminal board for the terminals 35 of the tube 32. It will be noted in Fig. 2 that the conductors for the tube 32 extend from engagement with the terminals 35 at the exterior surface of the handle 33 inwardly into the cavity and to electrodes of the tube 32. There are no loose conductor wires extending from the exterior of the handle 33. The terminals 35 can be conveniently formed of drops of solder that engage conductor ends projected through the plate 34 to the exterior surface of the handle 33, the terminals 35 being located on the surface of the handle where they will engage contacts 28 when the handle is positioned in the rotor 11.

The rotor 11 is provided with the slot 38 to receive and accommodate the handle 33. The stator 12 is preferably provided with the flattened face 39 that provides a gap in the cylinder 15 between the edges 40, the gap between edges 40 being wide enough for the handle 33 to pass between them. The cylindrical surface 15 is greater than a semicircle, and operates to confine the rotor 11 in the stator 12 as shown in Figs. 1 and 3. The side plates 42 preferably of dielectric material, are attachable to the side surfaces of the stator 12 by means of the screws 43 for example, to complete confinement of the rotor 11 in the stator 12.

The handle 33 is provided with the shoulders 50 that are preferably formed arcuate as shown to conform with the curvature of the cylinder 15 of the stator 12. It will be noted that the contacts 28 are confined within the pockets 31 of the rotor 11, and will not come out when the handle 33 is removed from its slot 38. When the handle 33 is inserted into the slot 38 it opposes the resiliency of the contacts 28, which operate to press its shoulders 50 into engagement with the cylindrical surface 15. Recesses 51 are provided in the edges 40 to receive the stem of the handle 33 when it is in the "off" position of Fig. 1 or the "on" position of Fig. 3. In the intermediate position of Fig. 6, the handle 33 can be pulled out of the slot 38 to be removed from the rotor 11 for replacement or repair, for example, the handle being removable between the edges 40 when in this intermediate position. In the intermediate position of Fig. 6, both contactors 20 and 21 are out of contacting engagement with the contacts 26 of the stator 12. In either the "off" or "on" positions of Figs. 1 and 3, when the contactors 20 and 21 respectively are in contacting engagement with the contacts 26 of the stator 12, the shoulders 50 of the handle 33 are held under the edges 40 to prevent removal of the handle 33 from the rotor 11. This prevents damage or injury by the switch being tampered with when the handle 33 is removed.

A convenient means for mounting the switch of the disclosed practical embodiment, when it is to be used as a wall-outlet switch, is illustrated in Figs. 5 and 6. The switch is attached to the escutcheon plate 45, by the screws 46, for example, which fasten the escutcheon plate 45 to the stator 12. The switch is fastened to the wall outlet by means of the screws 47, the escutcheon plate 45 being preferably provided with the slots 48 which adapt the switch to the standard switch box 53.

The switch plate 55 may be provided, to be attached to the escutcheon plate 45 by means of the screws 56. The switch plate 55 may be of standard construction, and the escutcheon plate 45 drilled and tapped for the screws 56 to adapt

the switch to the standard switch plate. The switch plate 55 includes the slot 58 through which the handle 33 projects into exposed position for manual operation of the switch. The slot 58 operates to engage the shoulders 50 of the handle 33 when the switch plate 55 is attached, requiring the switch plate 55 to be removed when it is desired to replace or repair the handle 33. The handle 33, accordingly, is an article of manufacture that can be conveniently replaced in the switch.

The particular use for the switch embodiment shown in the drawings is for a line with a load 52 in electrical circuit therewith.

See Fig. 7. The load 52, as indicated schematically, may include electric lights in a room, and the load may include various other electrical apparatus. In the disclosed circuit the handle 33 is caused to glow when the room is dark by the switch being in "off" position. The line circuit is closed through the continuous conductor contactor 20 by the rotor 11 being in "on" position of Figs. 1 and 2, and this operates to energize the load 52. When the switch is thrown to "off" position of Figs. 3 and 4, the line circuit is closed through the multiple-contact contactor 21, placing the glow-tube 32 and the resistor 36 in series with the load 52. With a resistor 36 selected for proper performance of the glow-tube 32, the resistance in the load circuit is so high that the load 52 draws insufficient current for its operation. In the case of the load being one or more electric lights, either including or not including various other electrical apparatus, the current is too low to produce incandescence of the electric lights, and the current consumption of the circuit is accordingly very low. The glow-tube 32, accordingly, is inexpensive to operate.

The embodiment disclosed in the drawings illustrates one practical application of the invention, but the disclosure is not to be construed as limiting the invention. The scope of the invention is determined by the accompanying claims.

The invention described herein may be manufactured and used by or for the Government of the United States of America for governmental purposes without the payment of any royalties thereon or therefor.

I claim:

1. In an electrical switch, companion members comprising a rotor and a stator rotatable relative to each other in registration on a cylinder of registry between the members, one member comprising a cylindrical surface of dielectric material coincident with the cylinder of registry, inserts of conductor material in the cylindrical surface spaced apart lengthwise thereof and comprising electrical contacts, the other member comprising a notch projecting away from the cylinder of registry and extending lengthwise thereof, the notch comprising dielectric walls, a roller confined in the notch and comprising contact cylinders of conductor material spaced apart lengthwise of the roller and of the cylinder of registry in position to register each with a companion contact of the other member, resilient means in the notch in backing relationship with the roller and operating to press it radially against the cylindrical surface of the other member, and means to rotate the rotor relative to the stator to roll the contact cylinders of the roller alternatively into and out of engagement with their respective companion contacts of the other member.
2. In an electrical switch, companion members of dielectric material comprising a rotor and a

stator rotatably relative to each other in registration on a cylinder of registry between the members, one member comprising a cylindrical surface coincident with the cylinder of registry, inserts of conductor material in the cylindrical surface spaced apart lengthwise thereof and comprising electrical contacts, the other member comprising a notch projecting away from the cylinder of registry and extending lengthwise thereof, a roller confined in the notch and comprising contact cylinders of conductor material spaced apart lengthwise of the roller and of the cylinder of registry in position to register each with a companion contact of the other member, resilient means in the notch in backing relationship with the roller and operating to press it radially against the cylindrical surface of the other member, and means to rotate the rotor relative to the stator to roll the contact cylinders of the roller alternatively into and out of engagement with their respective companion contacts of the other member.

3. In an electrical switch, companion members comprising a rotor and a stator rotatable relative to each other in registration on a cylinder of registry between the members, the stator comprising a cylindrical surface of dielectric material coincident with the cylinder of registry, inserts of conductor material in the cylindrical surface spaced apart lengthwise thereof and comprising electrical contacts, the rotor comprising a notch projecting away from the cylindrical of registry and extending lengthwise thereof, the notch comprising dielectric walls, a roller confined in the notch and comprising contact cylinders of conductor material spaced apart lengthwise of the roller and of the cylinder of registry in position to register each with a companion contact of the stator, resilient means in the notch in backing relationship with the roller and operating to press it radially against the cylindrical surface of the other member, and means to rotate the rotor relative to the stator to roll the contact cylinders of the roller alternatively into and out of engagement with their respective companion contacts of the stator.

4. In an electrical switch, companion members comprising a rotor and a stator rotatable relative to each other in registration on a cylinder of registry between the members, one member comprising a cylindrical surface of dielectric material coincident with the cylinder of registry, inserts of conductor material in the cylindrical surface spaced apart lengthwise thereof and comprising electrical contacts, the other member comprising a notch projecting away from the cylinder of registry and extending lengthwise thereof, the notch comprising dielectric walls, a roller confined in the notch, the roller comprising contact cylinders of conductor material and a dielectric piece holding them spaced apart lengthwise of the roller, the contact cylinders of the roller being held spaced apart lengthwise of the cylinder of registry in position to register each with a companion contact of the other member, resilient means in the notch in backing relationship with the roller and operating to press it radially against the cylindrical surface of the other member, and means to rotate the rotor relative to the stator to roll the contact cylinders of the roller alternatively into and out of engagement with their respective companion contacts of the other member.

5. In an electrical switch, companion members comprising a rotor and a stator rotatable relative

to each other in registration on a cylinder of registry between the members, one member comprising a cylindrical surface of dielectric material coincident with the cylinder of registry, inserts of conductor material in the cylindrical surface spaced apart lengthwise thereof and comprising electrical contacts, the other member comprising a notch projecting away from the cylinder of registry and extending lengthwise thereof, 10 the notch comprising dielectric walls, a roller confined in the notch, the roller comprising contact cylinders of conductor material and a dielectric piece holding them spaced apart lengthwise of the roller, the contact cylinder of the roller being held spaced apart lengthwise of the cylinder of registry in position to register each with a companion contact of the other member, terminals companion to the contact cylinders of the roller and positioned in the notch-containing 15 member through the body thereof opposite the notch, a spring for each contact cylinder of the roller in backing relationship therewith and extending through the body of the member in electrical circuit with the contact cylinder and its 20 companion terminal in the notch containing member, the springs operating to press the contact cylinders of the roller radially against the cylindrical surface of the other member, and means to rotate the rotor relative to the stator to roll the contact cylinders of the roller alternatively into and out of engagement with their respective companion contacts.

6. In an electrical switch, companion members comprising a rotor and a stator rotatable relative to each other in registration on a cylinder of registry between the members, one member comprising a cylindrical surface of dielectric material coincident with the cylinder of registry, inserts of conductor material in the 35 cylindrical surface spaced apart lengthwise thereof and comprising electrical contacts, the other member comprising a notch projecting away from the cylinder of registry and extending lengthwise thereof, the notch comprising dielectric walls, a roller of conductor material confined in the notch and comprising contact cylinders spaced apart lengthwise of the roller and of the cylinder of registry in position to register each with a companion contact of the 40 other member, resilient means in the notch in backing relationship with the roller and operating to press it radially with its contact cylinders engaging the cylindrical surface of the other member, and means to rotate the rotor relative to the stator to roll the contact cylinders of the roller alternatively into and out of engagement with their respective companion contacts of the other member.

7. In an electrical switch, companion members comprising a rotor and a stator rotatable relative to each other in registration on a cylinder of registry between the members, one member comprising a cylindrical surface of dielectric material coincident with the cylinder of registry, inserts of conductor material in the cylindrical surface spaced apart lengthwise thereof and comprising electrical contacts, the other member comprising a plurality of notches with dielectric walls and being disposed spaced apart circumferentially of the member, each notch projecting away from the cylinder of registry and extending lengthwise thereof, a contactor confined in each notch, each contactor comprising a roller, one contactor comprising a continuous piece of conductor mate-

rial formed to include contact cylinders spaced apart lengthwise of the contactor, the contact cylinders being disposed in position to register each with a companion contact of the other member when the contactor thereof is confined in the notch, resilient means in the notch containing the continuous-conductor contactor and operating to press it radially to engage its contact cylinders with the cylindrical surface of the other member, the other contactor comprising contact cylinders of conductor material and a dielectric piece holding them spaced apart lengthwise of the contactor, the contact cylinders of the second contactor being held spaced apart lengthwise of the cylinder of registry in position to register each with a companion contact of the other member when the second contactor is confined in its notch, terminals companion to the contact cylinders of the second contactor and positioned in the notch-containing member through the body thereof opposite the second contactor, a spring for each contact cylinder of the second contactor in backing relationship therewith and extending through the body of the member each in electrical circuit with its contact cylinder and companion terminal, a translucent handle carried by the rotor, an electric light contained in the handle and being connected electrically in circuit with the terminals companion to the contact cylinders of the second contactor, the handle being operable to rotate the rotor relative to the stator to roll the contact cylinders of the several contactors each selectively into and out of engagement with and the contactors severally alternatively into and out of contacting engagement with their respective companion contacts of the other member.

8. In a switch as defined in claim 1, the means for rotating the rotor relative to the stator comprising a handle detachably attached to the rotor, positioning the rotor in predetermined position relative to the stator with the contactor of one member out of engagement with the contacts of the other operating to locate the handle for removal from the switch.

9. In a switch as defined in claim 7, the handle being positionable for removal from the switch when the rotor is positioned with both contactors of the one member out of engagement with the contacts of the other member.

10. A removable handle for an electrical switch comprising a body member of translucent material, an electron discharge glow tube contained in the handle, the body member comprising a cavity of a size and shape to receive the tube and hold it positioned in the handle, a set of contacts attached to the external sur-

face of the handle in position for each contact to engage a companion contact in the switch by the handle being positioned in the switch, and conductors for each contact of the handle extending inwardly of its exterior into the cavity, each conductor extending from a contact to an electrode of the tube.

11. A removable handle for an electrical switch comprising a body member of translucent material, an electron discharge glow tube contained in the handle, the body member comprising a cavity of a size and shape to receive the tube, a closure member enclosing the tube in the handle and comprising a set of contacts attached to the external surface thereof in position for each contact to engage a companion contact in the switch by the handle being positioned in the switch, and a conductor extending from each contact of the handle inwardly from the exterior of the handle into the cavity and to an electrode of the tube.

12. For an electrical line with a load in circuit therewith, a switch comprising a stator and a rotor, the stator comprising terminals connected to the line in series with the load, the rotor comprising a translucent handle for operating it, an electron discharge glow tube in the handle, and "on" and "off" contactors in the rotor positionable alternatively in electrical circuit with the terminals under operation of the rotor by the handle, the "on" contactor comprising a continuous conductor, the "off" contactor comprising contacts separated by insulation each companion to a terminal, an electrical circuit from the contacts of the "off" contactor through the glow tube and comprising a resistor in series with the tube.
